UNITED STATES PATENT OFFICE.

GROVER C. BROWN, OF JOHNSTOWN, PENNSYLVANIA.

CLOTHES DRIER.

Application filed October 18, 1921. Serial No. 508,482.

To all whom it may concern:

Be it known that I, GROVER C. BROWN, a citizen of the United States, and a resident of the city of Johnstown, county of Cambria, and State of Pennsylvania, have invented certain new and useful Improvements 5 in Clothes Driers; and I do hereby declare the following to be a full, clear, and exact description of the invention, such as will enable others skilled in the art to which it 10 pertains to make and use the same.

My invention relates to an apparatus for holding clothes and other textiles or similar articles for the purpose of drying them after 15 washing, or for aerating the same, and is particularly adapted for use indoors, in kitchens, in laundries or on porches, but may also be used outdoors if desired.

My apparatus in general consists of a pair 20 of guides or slideways which are mounted opposite and substantially parallel to each other on the walls of a room or elsewhere and are provided with carriages adapted to slide or roll up or down within the guides 25 or slideways, and the carriages are provided with hooks or other means extending outwardly therefrom on which lines, either of fibrous material or wire, may be removably secured. The carriages are also provided 30 with means for moving them up or down simultaneously for the purpose of carrying the line upwardly after clothes are attached thereto and for lowering the same for the purpose of removing clothes or articles there- 35 from.

My apparatus may have one line or may have a plurality of lines or a plurality of apparatus may fill a room or space more or less to provide lines sufficient to hold any 40 desired quantity of material to be dried.

My carriages are provided with a flexible attachment and with the necessary sheaves around which it is rove, and a winding sheave or sprocket wheel provided with a 45 hand crank whereby the carriages may be raised or lowered simultaneously, carrying the line with them, and I may also provide means for locking the line in position to prevent the weight thereon from lowering it.

Having thus given a general description 45 of my invention, I will now, in order to make the matter more clear, refer to the annexed sheet of drawings, which form part of this specification, and in which like characters refer to like parts.

Figure 1 is a vertical longitudinal sectional elevation of my improved device, illustrating the application of my invention; Figure 2 is a transverse sectional elevation 60 through one of the guides, boxes or housings taken on the line II—II of Figure 3; Figure 3 is a front elevation of one of the guides or boxes; Figure 4 is a front elevation of the other guide or box; Figure 5 is a transverse sectional elevation through two guides 65 or boxes taken on the line V—V of Figure 3, and Figure 6 is a transverse sectional elevation through one of the guides of a slightly modified form.

Referring now to the characters of reference on the drawings:—1 represents the side walls of a room or building to which my apparatus may be secured, but I wish it understood my apparatus may be supported otherwise if desired on convenient posts or 70 other structures, either in or out of doors. 2 represents the ceiling of a room, 3 and 4 are the guides or boxes in which a part of the working portion of my apparatus is mounted and guided; these guides or boxes 75 are provided with rear walls 5 and 6, and 7 are the screws which attach the boxes or guides to the walls of a room or other structure. The guides or boxes are provided with 80 slots 9 in the front walls or closures 8 thereof, through which the hooks 12, secured to the carriages 10, are adapted to project in order to receive the line 13, which line may be either of fibrous material or wire and may or may not be provided with means for 85 stretching same taut. Within these guides I mount the carriages 10, which are preferably provided with rollers 11 to afford a rolling contact with the front walls or closures of the boxes. These rollers 11 are 90 provided to afford easy means for traversing the carriages within the boxes. The carriages are provided with a sprocket chain 14, which is attached to the carriages as at 15 and passes around the sprocket wheel 16, 100 which is provided with a hand crank 17 attached to the shaft 18. At the upper end of the box or guide 3 I provide sheaves 19 and 20, and at the upper end of the box 4 I provide sheaves 21 and 22, these sheaves 105 being mounted on bolts 23 provided with spacing sleeves 24 as illustrated. I also provide at the bottom of the box 4 another sheave 25 mounted on a bolt 26, which is provided with spacing sleeves 27. The 110

sprocket chain 14 need only be provided for the lower portion of the flexible member extending from one of the carriages down and around the sprocket wheel 16 and upwardly 5 again for a short distance equal to the other portion. The other portion of the flexible member may be either a sprocket chain or a wire cable.

I prefer to form the end of the flexible 10 member from sprocket chain as this insures positive movement without slippage, while the other parts may be of sprocket chain or of wire cable.

The flexible member has one end secured 15 at 15 to the carriage 10 in the left hand box 3 shown in Figure 1, passes downwardly and thence around the sprocket wheel 16, thence upwardly and around the sheave 19, thence across near the ceiling of the room or top of 20 the apparatus and around the sheave 21 in the opposite guide and thence downwardly and secured to the carriage in the right hand box 4. This flexible member 14 may be continuous or any other flexible member may be 25 secured to the right hand carriage in box 4, passing downwardly and thence around the bottom sheave 25, thence upwardly and around the sheave 22, thence across the top 30 of the room and around the sheave 20 and thence downwardly and secured to the left hand carriage 10 in the box 3. The flexible member may be either continuous and secured to the two carriages, or it may be discontinuous and secured to two ends of each 35 carriage. I may also provide a pin 28 which is adapted to be inserted through the hole in the side wall of the box 3 and thence inserted between portions of a link of the sprocket chain, and when this is in position 40 the apparatus will be locked to prevent its movement.

As illustrated in Figure 6, 29 is a carriage 45 with two hooks 31, each of which is adapted to receive a line 13 secured thereto, thereby providing a duplicate apparatus and more can be provided if desired. 30 are the rollers of the carriage which roll against the front closure 8. These hooks 31 pass through the slots 32 in the front walls of the box.

50 The operation of my apparatus is as follows: The line or lines 13, which are preferably provided with looped ends with or without a thimble thereon, have these ends on the hooks 12 or 31. The carriages are lowered to a convenient position and height above the floor by turning the hand crank 17. The clothes or other material are placed in 55 position on the line, secured by clothes pins or otherwise, and by turning the crank 17 in proper direction the line 13 is moved upwardly carrying the clothes up or out of the way and in proper position for drying. In order to hold the lines in position a pin 28 may be inserted in the hole provided therefor and in one of the links of the sprocket 60

chain. Reversal of this operation will lower the clothes for their removal, after which others may be put in their place.

Instead of using a crank I may raise and lower my apparatus by pulling the lines 70 thereof, which may be exposed for this purpose, but I prefer to operate by the crank and sprocket wheel as previously explained. The crank 17 is also removable from the shaft 18 so it will be out of the way and not 75 interfere with the movement of people in the neighborhood of the apparatus, and the same crank may be used on various shafts in case a plurality of driers are installed.

One of the particular features of my invention resides in the fact that the working 80 portions of my apparatus are neatly enclosed in the boxes forming a sightly appearance and are also protected from dust and inaccessible to persons who might meddle with 85 the mechanism.

It wil also be noted that my guides or 90 boxes are practically a complete closure for the contained apparatus, with the exception of the small narrow slots through which the ends of the hooks project, making a neat-appearing construction.

By means of my arrangement the apparatus may be installed in a room or elsewhere and clothes raised to the proper height 95 so they will not interfere with persons in the room and will be in the best position for drying and aerating.

If desired I may cover the exposed lines 100 near the ceiling by boxing or molding, but this is not ordinarily necessary.

It should also be noted that I can have a 105 number of lines attached to the same carriage and operated by the same raising and lowering mechanism.

In arranging my apparatus for shipment, the flexible members may be joined near the ceiling and special means for tying and adjusting to proper length will there be made, and this will also provide means for adjusting the lines thereafter if slack develops from use. The guide boxes may also be easily attached to the walls of a room or other structure by removing the front closure 8, so that the screws 7 may be driven, or a screw driver may be inserted through the slots 9 to drive the screws 7.

110 Although I have shown and described my invention in considerable detail, I do not wish to be limited to the exact and specific 120 details thereof, as shown and described, but may use such modifications in, substitutions for, or equivalents as pointed out in the claims.

Having thus described my invention, what 125 I claim and desire to secure by Letters Patent is:—

1. In a clothes drier, a pair of substantially parallel box section guides spaced apart, each provided with a front closure, a 130

- carriage mounted in each guide and provided with rollers adapted to roll on said front closure and to be guided by said guide, an operating wheel provided with a hand 5 crank, a line secured to and extending between said carriages arranged at substantially a right angle to the axes of the rollers, a flexible connection secured to both carriages and passing around said operating 10 wheel, and sheaves mounted in and near the ends of the guides over which said flexible connection passes, whereby said carriages may be positively traversed up and down in the box guides simultaneously.
- 15 2. A clothes drier comprising a pair of box-shaped guides, each provided with a front closure, substantially parallel and spaced apart, a carriage mounted in each of said guides and provided with anti-friction 20 wheels adapted to bear and roll against the front closure of said guide, a line secured to the opposite carriages and extending therebetween, a flexible connection secured to one of the carriages, a plurality of sheaves 25 mounted in the guides around which the flexible connection passes as hereinafter described, a drive wheel mounted in and near the lower end of one of said guides and around which said flexible connection passes, 30 thence upwardly past said carriage and around a sheave mounted in and near the top of said guide, thence across and over another sheave mounted in and near the top of the other guide, thence downwardly and se- 35 cured to the opposite carriage, thence downwardly and around another sheave mounted in the guide, thence upwardly and around another sheave mounted in and near the top of the second guide, thence across to the other 40 guide, and around another sheave mounted in and near the top thereof, thence downwardly and secured to the first named carriage, the drive wheel being provided with a crank, whereby said carriages may be 45 moved upwardly and downwardly simultaneously.
3. In a clothes drier, a pair of guides of box-like construction arranged apart and spaced simultaneously parallel, each being provided with a removable front closure, a 50 carriage mounted in each guide provided with anti-friction rollers adapted to bear and roll on the inside of the front closure of the guide, a sprocket wheel mounted near the lower portion of one of the guides pro- 55 vided with an operating crank, a sprocket chain passing around said wheel one end of which is secured to the adjacent carriage and the other end provided with a flexible connection secured to the carriages, sheaves 60 mounted in and near the ends of the guides and over which sheaves the said flexible connection passes in such a manner that the revolution of the crank causes the two carriages to move upwardly or downwardly si- 65 multaneously.
4. A clothes drier comprising a pair of substantially parallel guides of box-like construction spaced apart, and provided with removable front closures, a carriage in 70 each guide provided with anti-friction rollers adapted to bear and roll on the inside of the front closure of the guide, a slot extending longitudinally of the front closure of each guide, a hook mounted on each carriage and adapted to project through said slot, a line the ends of which are secured to said hooks, a sprocket wheel mounted near the lower portion of one of the guides and provided with an operating crank, a 80 sprocket chain passing around said wheel one end of which is secured to the adjacent carriage and the other end provided with a flexible connection secured to the carriages, sheaves mounted within and near the ends of 85 the guides over which the said flexible connection passes in such a manner that the revolution of the crank causes the two carriages and the lines secured thereto to move upwardly and downwardly simultaneously. 90

In witness whereof I hereunto affix my signature.

GROVER C. BROWN.
